8 Claims. (Cl. 28—44)

ABSTRACT OF THE DISCLOSURE

A device for drawing warp threads into a reed in a weaving machine including a drawing-in attachment having a reciprocating reeding hook supported between the reed and the heddles for movement parallel to the reed and guide means supported on said drawing-in attachment forming at least one inlet opening for the warp threads facing one of the upper and lower baulks of the reed for guiding said warp threads individually onto said reeding hook.

This invention relates to weaving devices and more particularly to improvements in a device for drawing warp threads into reeds.

Known attachments for drawing warp threads into reeds are designed in such a way that they operate with the reed inclined downwardly in front of the machine operator while the harness with the warp thread already drawn through its heddles and ready to be drawn into the reed, is suspended behind the reed and at some distance above it. In this case, the machine operator takes one warp thread after the other and guides it downwardly into the inlet openings of the drawing-in attachment. The drawing-in attachment itself then takes up the warp thread offered to it and, with the aid of a hook, draws it obliquely downward into a dent of the reed.

In cases where warp threads have to be drawn directly into the loom, which may be necessary, for example, when a reed is damaged and has to be replaced by another, the known drawing-in attachments are impractical and difficult to operate. In this case, the eyes of the heddles are located beneath the reed, with the result that each warp thread to be drawn in must be fetched from below, out of the field of vision of the operator, and guided toward the inlet hole of the drawing-in attachment over the reed. This is a troublesome and complicated operation.

According to the present invention, a drawing-in device is provided with a guide member providing inlet openings or entrances to the reed which face the upper and lower baulks of the reed. These openings enable the warp threads to be drawn in in such a way as to be conveniently offered both downwardly and upwardly to the drawing-in attachment, thereby greatly facilitating the drawing-in operation.

It is therefore an object of the present invention to provide a drawing-in attachment for drawing warp threads into reeds which is more versatile and efficient than devices of a similar nature known heretofore.

It is another object of the present invention to provide a drawing-in attachment of the type disclosed herein which is selectively adjustable as to position so as to be capable of drawing-in from either the upper or lower side of the reed.

It is a further object of the present invention to provide a drawing-in attachment of the type disclosed herein presently used apparatus of various configurations.

These and other objects, features and advantages of the which is of simple construction and easily adaptable to instant invention will become more apparent from the following detailed description of the invention when taken

2

with the accompanying drawings, which show several embodiments of the instant invention, and wherein:

FIGS. 1 and 2 are diagrammatic cross-sections through a drawing-in attachment provided with two inlet openings, one facing the lower baulk and the other facing the upper baulk of the reed;

FIGS. 3 and 4 show a drawing-in attachment provided with one inlet opening which is formed in such a way that it can alternately face the upper and lower baulks of the reed;

FIGS. 5 and 6 show a drawing-in attachment provided with one inlet opening which is non-variable relative to the drawing-in attachment, mounted on a frame, the upper section of which can be pivoted about its longitudinal axis and locked in two positions facing each other at an angle of approximately 180°; and

FIG. 7 shows a drawing-in attachment which can be brought into two symmetrical positions relative to the reed, on a non-pivotal frame.

The device shown in FIGS. 1 and 2 comprises a support frame 1 for the drawing-in attachment along whose supporting tubes 2 the drawing-in attachment can move on rollers 4 driven by conventional drive means. When it rolls, the drawing-in attachment 3 moves a reeding hook 5 in a reciprocating manner by any known means through the dent of a reed 6 to catch the threads 7 and draw them into the reed. In order that warp threads 7 may be rapidly and easily pushed onto the hook 5, the guide member 8 is provided, which contacts the successive threads as the attachment 3 moves across and guides them onto the hook 5. Both the reeding hook 5 and the guide members 8 are symmetrically designed so that they form complementary surfaces with the result that identical inlet openings 9 and 10 are formed which face toward the upper and lower baulks, respectively, of the reed 6.

As far as the procedure of operation of the arrangement illustrated in FIG. 1 is concerned, a harness 11 is suspended in a somewhat elevated position relative to the reed, which may be done, for example, during drawing-in 40 of the warp threads into the reed, by means of a "reaching" machine after the warp threads have been drawn into the harness. In this case, the warp threads 7 are guided one at a time into the inlet opening 9, taken up by the lower hook of the reeding hook 5 and drawn through the dent of the reed. When all of the threads have been drawn into the reed, the reed is pivoted upwardly, in a clockwise direction, as taken in FIG. 1, to its proper position adjacent the heddles.

The same device as shown in FIGURE 1 is illustrated in FIGURE 2, the only difference being that, in this case, the frame for mounting the device is not provided on the floor; instead, the device is suspended on a separate supporting arm 12 from the two ends of the harness by means of a support hook 13. In this case, the warp threads 14 travel upward and have to be introduced into the inlet opening 10. It is therefore possible by means of the attachment shown in FIGS. 1 and 2 to feed the warp threads both upward and downward to the reeding hook without any need for re-arrangement.

FIGS. 3 and 4 illustrate different designs for the guide member 8 from that shown in FIG. 1. The guide member 15 is mounted on a support 16 rigidly connected to the drawing-in attachment 3. Since the support 16 and reeding hook 17 are positioned symmetrically relative to the reed, the guide member 15 may be alternately placed in the positions shown in FIGS. 3 and 4 by merely reversing the position of the guide on the attachment 3. In this way, the warp threads 18 may again be introduced upward or downward into the reeding hook, as is the case with the arrangement shown in FIGS. 1 and 2. The attachment shown in FIGS. 3 and 4 has the advantage that the guide

member is not quite so heavy with the result that the attachment is easier to handle.

FIGS. 5 and 6 illustrate a drawing-in attachment 19 which comprises a reeding hook 20 having only one point. Accordingly, the guide member 21 is designed in such a way that it is only effective on one side and defines one inlet opening 22 for the thread to enter the reed. The drawing-in attachment as a whole is displaceable along supporting tubes 24 on rollers 23. In this case, at least three such rollers 23 are required in order to guide the attachment 19 along the supporting tubes 24 in such a way that it cannot be derailed therefrom. The two supporting tubes 24 are fixed at both ends of the frame to supports 25 which are so mounted on the feet 27 of the frame as to be rotatable about pivots 26. A known type of locking mechanism of any conventional configuration (not shown) enables the supports 25 to be locked in at least two positions facing each other at an angle of approximately 180° on the feet 27. In the position shown in FIG. 5, the warp threads are guided downward over the reed and introduced upward into the outlet opening by the guide 21. If the supporting tubes 24 together with their supports 25 are turned through 180° into the position shown in FIG. 6, the warp threads are guided upward over the reed and downward into the inlet opening 22 by the guide member 21, this time from the other side of the frame. Since, in the arrangement shown, the drawing-in attachment 19 remains on the upper part of the frame as it pivots, the attachment must be guided on the supporting tubes in such a way that it cannot be derailed therefrom.

Finally, FIG. 7 shows a drawing-in attachment 28 which only differs from the attachment shown in FIG. 5 in that it is releasably connected to the frame 29 by means of a wing nut 30 so as to permit rotation of the attachment about a transverse axis. In this case, a groove 31 in the drawing-in attachment 28 enables the attachment to be fixed in two positions facing each other at an angle of 180°. Under these circumstances, it is no longer necessary for the supporting tubes 32 to be pivotally mounted. They can in fact be directly mounted in stationary or fixed feet 33. The embodiment shown in FIG. 7 enables warp threads to be drawn-in exactly the same way as in the embodiment shown in FIGS. 5 and 6.

While we have shown and described several embodiments in accordance with the present invention, it is understood that the same is not limited thereto but is susceptible of numerous changes and modifications as known to a person skilled in the art, and we therefore do not wish to be limited to the details shown and described herein, but intend to cover all such changes and modifications as are encompassed by the scope of the appended claims.

We claim:

1. In a weaving machine having a reed and heddles, a device for drawing warp threads into said reed comprising a drawing-in attachment including a reeding hook and means for reciprocating said reeding hook in response to indexing movement of said attachment, support means for

supporting said drawing-in attachment adjacent said reed between said reed and said heddles for movement parallel to said reed with reeding hook extending during a portion of its stroke through a dent in said reed, the improvement essentially consisting of guide means supported on said drawing-in attachment forming at least one inlet opening for the warp threads facing one of the upper and lower baulks of the reed for guiding said warp threads individually onto said reeding hook.

10 2. A device for drawing warp threads into a reed as defined in claim 1 wherein said guide means forms first and second inlet openings facing the upper and lower baulks of the reed, respectively.

15 3. A device for drawing warp threads into a reed as defined in claim 2 wherein said reeding hook is provided with two hook portions facing, respectively, the upper and lower baulks of the reed.

20 4. A device for drawing warp threads into a reed as defined in claim 1 wherein said guide means provides only one inlet opening for the warp threads and is removably supported on said drawing-in attachment so as to be positionable with said inlet opening facing either of the upper and lower baulks of said reed.

25 5. A device for drawing warp threads into a reed as defined in claim 4 wherein said support means includes a lower support base portion and an upper guide portion, said upper guide portion being pivotable on said lower support base portion about an axis parallel to said reed so as to selectively position said inlet opening facing at least one of the baulks of said reed.

30 6. A device for drawing warp threads into a reed as defined in claim 5 wherein the upper guide portion of said support means is provided with a pair of parallel rail members, said drawing-in attachment being supported between said rails by a plurality of wheels engaging with the facing surfaces of said rails.

35 7. A device for drawing warp threads into a reed as defined in claim 4 wherein said drawing-in attachment is mounted on said support means for pivoting movement about an axis transverse to said support means and said reed so as to selectively position said inlet opening facing at least one of the baulks of said reed.

40 8. A device for drawing warp threads into a reed as defined in claim 7 wherein said support means is provided with a pair of rail members, said drawing-in attachment being supported between said rails by a plurality of wheels engaging with the facing surfaces of said rails.
